UNITED STATES PATENT OFFICE.

REAMEY H. DYER, OF ROANOKE, VIRGINIA.

WASTE RETAINER.

Application filed September 29, 1927. Serial No. 222,773

This invention relates to waste retainers for car axle boxes, and is in the nature of an improvement to, or modification of, the waste retainer disclosed and claimed in my prior application, Ser. No. 125,363, filed July 28, 1926.

The device of said application is a single piece of metal, preferably pressed steel, comprising a transverse member adapted to extend across the face of the journal collar, and a leg or side member extending back on each side of the journal, the outer edges of each of said three members having a downwardly extending flange to engage and retain the waste, while from the inner edge of each side member extends upwardly a cheek member which is bent over at its top to form a horizontal bearing surface, said surface being adapted to be engaged by the bottom faces of the bearing brass, whereby the retainer is kept in its proper position.

The device, constituting the present invention, is similar to the said prior device, but instead of being an integral structure, is made in two halves, constituting right and left hand sections, in order to facilitate its introduction to and removal from car journal boxes. Owing to the presence of the collar on the end of the journal and to the width of the bearing surfaces on the cheek members, it is not always possible to insert or remove the former integral device from the boxes, without jacking up the box, which operation the trainmen will not ordinarily perform while the train is en route, so that, in the event of a hot box, the waste cannot be removed until the car reaches a repair shop. To overcome this objection, I reduce the width of said bearing surfaces and divide the retainer, which otherwise may be identical with that of my said prior application, or with that disclosed in another application filed by me on July 25, 1927, Ser. No. 208,203, by a central cut through the end transverse member and the two parts may be hinged together, but, in any case, are provided with means for detachably securing them together when in place, all as is hereinafter specifically described with reference to the accompanying drawing, in which

Fig. 1 is a central longitudinal section through a box equipped with the improved retainer;

Fig. 2 is a cross-section on line 2—2 of Fig. 1;

Fig. 3 is a plan view of one form of the retainer;

Fig. 4 is a cross-section on line 4—4 of Fig. 2;

Fig. 5 is a plan view of a modified form; 60

Fig. 6 is a cross-section of the same on line 6—6 of Fig. 5, and

Fig. 7 is an underneath plan view of the front end of this form of retainer.

In these views, the box 17, brass 18, wedge 19 and journal 20, having collar 21, are all as usual, and are only shown to illustrate the location of the retainer in use.

As in my former applications aforesaid, the retainer comprises the transverse end member 1, having downwardly projecting flanges 2 and 3, and the legs or side members 4, having the flanges 5 and the upstanding cheek members 6, flanged on their tops to provide horizontal bearing surfaces 7 to engage under the brass 18. Said surfaces, however, are of less width than in the prior forms and in the present instance, the front member 1 is divided in the center by the cut 8, thus changing the device into a two-part structure composed of 70 right and left hand sections, which are, or may be hinged together by the pintle 13, passed through the curled ears 14 and 15, formed on the abutting ends of the divided front member, respectively. 75

To detachably secure the parts together, I provide a form of latch which, as shown in Figs. 1—4, consists of a swinging member 9, pivoted at 10 to the front transverse portion of one of the parts, and engaging beneath a 80 tongue 11 on the other part. This tongue is or may be punched and struck up out of the metal of said other part and, after the latch has been swung into locking position under it, the free end of the tongue may be hammered or bent down, as shown at 12, to retain the latch in place, while said bent end can easily be raised by a screwdriver, for instance, when it is desired to remove the parts from the box. In Figs. 5—7, the latch has a notch in 100 its free end, which is adapted to engage a stud 16 carried by the other part of the front member 1.

Another feature of improvement and one which is applicable to all the forms of my retainer, consists in concaving the cheek members 6 on arcs concentric with the journal, so that the latter, in moving laterally, will contact said cheeks over substantially their entire surface instead of merely along a line. 110

This concave form of the cheek members 6 is shown at 22 in Figs. 5 and 6, which also well show the narrow form of the bearing surfaces, as also the top surfaces 23 of the cheek members, which, as appears also in Figs. 1 and 3, curve downwardly from the rear ends of said surfaces to the ends of the side members.

By reducing the width of the surfaces 7 which contact the journal bearing brass and 10 by dividing the retainer into two parts, either hinged together or not, it is rendered possible to so turn the parts that they can be removed and inserted without jacking up the bearing.

Having thus described my invention, what 15 I claim is:

1. A waste retainer for car axle journal boxes, comprising right and left hand sections, each composed of an end member and a side member, the latter having an upstanding flange on its inner edge to engage the journal brass, said members also having downward extending flanges on their outer edges, and a swinging latch to lock said end members together.
2. A waste retainer for car axle journal boxes, comprising right and left hand sections, each composed of an end member and a side member, upward extensions on said side members to engage the journal brass, a latch pivoted to one of said end members, and a tongue on the other end member to detachably retain said latch in closed position.

3. A waste retainer for car axle journal boxes, comprising right and left hand sections, each composed of a short transverse member adapted to lie in front of one half of the journal collar, and a side member adapted to lie alongside the journal, upward extensions on said side members to engage under the journal brass, and a hinged connection between said two transverse members.

4. A two-part waste retainer for car axle journal boxes, each part comprising an end portion, adapted to lie across one half of the outer face of the journal, and a side portion, adapted to lie alongside the journal and carrying an upward projection, adapted to be engaged by the journal bearing brass, a hinge connecting said end portions, and a latch to hold said portions against relative angular movement.

5. In a waste retainer for car axle journal boxes comprising an end member and side members, cheek members projecting upwardly from the inner edges of said side members and provided with horizontal flanges on their tops, adapted to engage the bottom surfaces of the bearing brass, the inner faces of said cheek members being concaved concentrically to the journal.

In testimony whereof I have hereunto set my hand.

REAMEY H. DYER.
